US0D1066111S

(12) **United States Design Patent** (10) **Patent No.:** **US D1,066,111 S**
(45) **Date of Patent:** **** Mar. 11, 2025**

(54) **BACKING FOR EARRING**

(71) Applicant: **Venus by Maria Tash, Inc.**, New York, NY (US)

(72) Inventor: **Maria Tashjian**, New York, NY (US)

(73) Assignee: **Venus by Maria Tash, Inc.**, New York, NY (US)

(**) Term: **15 Years**

(21) Appl. No.: **29/780,160**

(22) Filed: **Apr. 22, 2021**

(51) **LOC (15) Cl.** **11-01**

(52) **U.S. Cl.**

USPC **D11/88**

(58) **Field of Classification Search**

(57) **CLAIM**

The ornamental design for a backing for earring, as shown and described.

DESCRIPTION

FIG. 1 is a perspective view of a first embodiment of a backing for earring showing my new design;

FIG. 2 is a front view thereof;

FIG. 3 is a rear view thereof;

FIG. 4 is a left view thereof;

FIG. 5 is a right view thereof;

FIG. 6 is a top view thereof; and

FIG. 7 is a bottom view thereof.

FIG. 8 is a perspective view of a second embodiment of the backing for earring showing my new design;

FIG. 9 is a front view thereof;

FIG. 10 is a rear view thereof;

FIG. 11 is a left view thereof;

FIG. 12 is a right view thereof;

FIG. 13 is a top view thereof; and,

FIG. 14 is a bottom view thereof.

The broken lines shown in the drawings represent portions of the backing for earring and form no part of the claimed design.

1 Claim, 8 Drawing Sheets
